UNITED STATES PATENT OFFICE.

JOHN A. BADGER, OF ELLWOOD CITY, PENNSYLVANIA.

NUT-LOCK.

1,010,109.

Specification of Letters Patent. Patented Nov. 28, 1911.

Application filed July 7, 1910. Serial No. 570,754.

To all whom it may concern:

Be it known that I, JOHN A. BADGER, a resident of Ellwood City, in the county of Lawrence and State of Pennsylvania, have invented a new and useful Improvement in Nut-Locks, of which the following is a specification.

This invention relates to nut locks and its object is to provide a device for the purpose stated which is of simple construction, inexpensive to manufacture, which can be readily applied and also readily removed, and which will securely hold the nut against turning on the bolt.

The invention comprises the construction and arrangement of parts hereinafter described and claimed.

In the accompanying drawing Figure 1 is a side view of a bolt showing the nut and locking means in position, the nut and locking means being in section; Fig. 2 is an end view of the nut; Fig. 3 is a transverse section through the locking key and the cooperating portions of the nut and bolt; Fig. 4 is a detail side view of the locking key; and Fig. 5 is a side view of a modified form of locking key showing its condition prior to application.

In the drawing 1 represents a bolt provided with screw threads 2 for receiving the nut 3. The bolt and nut may be of any desired construction and of any desired size and form. In carrying out my invention the bolt is not modified in any particular, and the nut is merely modified to the extent of being provided with a groove 4 opening into the bore of the nut and extending parallel to the axis of said bore. The locking member comprises a key 5 which is adapted to be driven into the groove in the nut after the latter is on the bolt and bite into or grip the threads of the bolt and thereby hold the nut against rotation. This key is preferably provided with an acute edge or edges 7 to enable it to more readily bite into or grip the threads of the bolt. As shown in the drawing, said key is grooved on its inner face, as at 6, so as to provide two acute edges 7 which cut into the threads of the bolt and prevent the nut from working loose. The outer end of the key is preferably turned at right angles, as at 8, to lie against the outer face of the nut and present a gib or head to facilitate the driving of the key and also for engagement by a claw implement or the

like, to enable the key to be drawn out when it is desired to remove the nut.

The key 5^a shown in Fig. 5, is bent between its inner and outer ends, the bending being preferably somewhat closer to its inner end than to its outer end, so that in its normal or unused condition there is a portion, as at 10, lying inside of the inner longitudinal face of said key. When the key is driven into place the point 11 rides along the bottom of the groove in the nut, thereby causing the cutting edges 7 at the point 10 to more effectively bite into the threads of the bolt. The key is made of spring or resilient metal and this curved contour also assists in locking the key from accidental outward escape in case it should be slightly smaller than the groove in the nut.

The key shown in Fig. 5 is provided on its inner face with transverse grooves or notches 9, which when the key is driven in place will, due to the resiliency of said bent key, engage the threads of the bolt and prevent accidental escapement of the key even if the latter does not have a tight or driven fit in the groove in the nut.

The groove in the nut and the key are of substantially the same cross sectional contour. This may vary within wide limits. Preferably the groove is of concave shape in cross section, slightly more than semicircular, as illustrated, and the key of substantially circular cross section except for the groove 6 on the inner face.

With the form of key shown it is not necessary that it have a tight fit in the groove, since any tendency of the nut to turn on the bolt will cause a rotation of the key in the groove and cause either one or the other cutting edge to bite into the threads. For the same reason the key need not be made so large that its edges will materially distort the threads, as the locking effect would be secured in the manner stated whenever an effort was made to turn the nut. The consequence is that while the key will effectively lock the nut against accidental turning, it does not distort the threads so as to prevent the bolt and nut being used repeatedly. The opposite walls of the groove are parallel, and the opposite sides of the key are likewise parallel so that no wedging action is secured when driving the key in place.

In manufacturing the bolt and nut are made in the usual way. The groove 4 is

formed by the punch which punches the hole in the nut blank, it merely being necessary to provide the punch on one side with a rib formed to the shape of the desired groove.

5 The tapping of the nut does not affect this groove. As a consequence there is absolutely no additional cost in the manufacture of the bolt and nut. The key will preferably be made from a heavy steel wire which can be 10 drawn with the groove 6 in one face so as to provide the ribs or acute edges 7. The provision of this groove in the act of drawing the wire adds practically nothing to its cost. The keys are made from such wire by simple cutting and bending operations, as will be readily appreciated, so that their cost is practically no more than that of small nails. The nut lock described can therefore be manufactured at a very reasonable cost. It 15 is of very simple construction, effectively holds the nut against turning on the bolt, can be readily applied, and can be as readily removed to permit the nut to be taken from the bolt. The acute edges of the key do not 20 distort the bolt threads, or at least so little that the nut can be taken off with an ordinary wrench.

The key is not applied until the nut is turned fully, to the desired position. The 30 lock will bite the bolt at any point around the circumference of the latter, so that it is possible to draw the nut fully home and prevent looseness in the parts secured by the bolts.

35 What I claim is:

1. A nut lock comprising a nut provided with a groove parallel to its axis, and a key arranged to fit in said groove and provided at each of its inner longitudinal edges with 40 an acute edge arranged to bite the threads of the bolt, said key and groove being of substantially uniform cross section throughout and being of such shape in cross section that the key can be rocked on a longitudinal axis.

45 2. A nut lock comprising a nut provided with a groove parallel to its axis and concave in cross section, and a key arranged to be driven into said groove, said key being of substantially circular shape in cross section 50 and provided with a longitudinal groove on its inner edge to form a plurality of acute edges arranged to bite the threads of the bolt.

55 3. A nut lock comprising a nut provided with a groove parallel to its axis, and a key arranged to be driven into said groove, said key in its normal state being bent to provide intermediate its ends a portion projecting toward the axis of the nut and arranged to 60 bite the threads of the bolt.

4. A nut lock comprising a nut provided with a groove parallel to its axis, and a key arranged to be driven into said groove, said key being longitudinally grooved on the face toward the axis of the nut to provide a plurality of acute edges, and being bent intermediate its ends to provide a portion projecting toward the axis of the nut. 65

5. A nut lock comprising a nut provided with a concave groove parallel to its axis, and a key arranged to be driven into said groove, said key being of substantially circular cross section and longitudinally grooved on its inner face and having its outer end bent at substantially a right angle 75 to its body.

6. A nut lock comprising a nut provided with a groove parallel to its axis, and a key arranged to be driven into said groove, said key being formed of resilient metal and longitudinally grooved on its inner face and bent intermediate its ends to project a portion 80 toward the axis of the nut.

7. A nut lock comprising a nut provided with a groove parallel to its axis, and a key arranged to be driven into said groove, said key in its normal state being bent to provide intermediate its ends a portion projecting toward the axis of the nut and being provided on its inner face with transverse 85 grooves or notches and with a plurality of longitudinal acute edges arranged to bite the threads of the bolt.

8. A nut lock comprising a nut provided with a groove parallel to its axis, and a key 95 arranged to be driven into said groove, said key being longitudinally grooved to provide a plurality of acute edges arranged to bite the threads of the bolt, being bent intermediate its ends to provide a portion projecting toward the axis of the nut, and being provided on its inner face with transverse 100 grooves or notches.

9. A nut lock comprising a nut provided with a groove parallel to its axis and concave in cross section, and a key arranged to be driven into said groove, said key being substantially circular in cross section and provided with a longitudinal groove on its inner face to form a plurality of acute edges 110 arranged to bite the threads of the bolt, said key being formed of resilient metal and bent intermediate its ends to project a portion toward the axis of the nut.

In testimony whereof, I have hereunto set 115 my hand.

JOHN A. BADGER.
